UNITED STATES PATENT OFFICE.

COLIN HUTCHINS, OF LEAMINGTON, ONTARIO, CANADA.

COLLAPSIBLE MOLD CORE.

Application filed November 1, 1924, Serial No. 747,207, and in Canada November 22, 1923.

This invention relates to molds and has special reference to inner and outer forms by which blocks, walls or other structures may be economically and expeditiously produced from plastic material, as concrete.

The primary object of my invention is to provide inner-outer and finishing forms that may be assembled for the construction of a wall, the inner and outer form determining the thicknesses of the walls, and the finishing forms the nature of the exposed surfaces of the walls, it being possible to provide a wall with a finishing surface in imitation of brick, tile or any building material.

Another object of my invention is to provide a novel mold core for the production of hollow concrete blocks or tiles, the core walls being shiftable and arranged to be distended or retracted by mechanism within the core, and the same mechanism is arranged so that it may be easily operated and will afford means by which the core may be manipulated relative to a mold or outer form.

A further object of this invention is to provide outer molds or forms which may be built up similar to a wall and afford ready means for the attachment of scaffolds or platform supports, which will permit of a wall being progressively formed while other parts of the wall are being set or curved.

A still further object of this invention is to provide a finishing form that may be placed against a concrete wall and a facing molded on the wall, or the facing may be first placed on the wall and then the finishing form used to make an impression in the facing. In either instance the wall may have a face in imitation of any well known building material.

The above and other objects are attained by a construction that will be hereinafter described and then claimed, and reference will now be had to the drawings, wherein

Figure 1 is a plan of a mold core or inner form;

Fig. 2 is a longitudinal sectional view of the same partly broken away;

Fig. 3 is a perspective view of a portion of the mold core;

Fig. 4 is a perspective view of a portion of a wall showing my inner and outer forms as being used in the formation of said wall;

Fig. 5 is a perspective view of outer forms used in the formation of a block or tile;

Fig. 6 is a perspective view of a portion of the wall showing how the finishing form is employed in connection with a wall facing;

Fig. 7 is a vertical sectional view of a portion of the same;

Fig. 8 is a horizontal sectional view of a portion of the finishing form, and

Fig. 9 is a sectional view, similar to Fig. 7 showing the finishing form in a reverse position.

Reference will first be had to Figs. 1 to 3 inclusive showing the collapsible core or inner form used in the production of hollow walls, blocks, tiles or the like. The core comprises angle plates 1, 2, 3 and 4 and these plates are assembled so that the edges thereof will overlap, as at 5, and all of said angle plates cooperate in forming the core that has end and side walls providing a structure rectangular in cross section.

Intermediate the ends of the angle plates are angle bars 7 and at the angles of the plates 1 to 4 inclusive are flat bars 6. The angle bars 7 of the plates 1 and 3 are opposed to the angles 7 of the plates 2 and 4 and are connected by links 8. Similar links 9 connect the flat bars 6 and in consequence of such link connections the angle plates 1 and 3 can be shifted relative to the angle plates 2 and 4, preferably by raising one set of angle plates relative to the other.

At the overlapping edges 5 of the angle plates 1 and 3 is a vertically disposed connecting bar 10, pivotally connected by a series of toggle members 11 to the angle bars 7 of the angle plates 1 and 3, so that when the connecting bar 10 is raised the angle plate 1 will be drawn towards the angle plate 3.

Pivots connected to the angle bar 7 of the angle plate 3 is an operating lever 12 pivotally connected, as at 13, to the upper end of the connecting bar 10, and said operating lever has an inset handle portion 14.

The angle plates 2 and 4 are articulated in a manner similar to the angle plates 1 and 3 and the levers 12 may be used for bodily lifting the collapsible core.

At the upper edges of the angle plates 1 and 3 are angle ledges 15 which will facilitate placing one core on top of another.

Reference will now be had to Figs. 4 and 110

5 showing the outer forms used in the formation of a concrete block 16 or a hollow wall 17; one of the hollow portions of the wall having a collapsible core therein. 5
5 Each outer form comprises a rectangular frame 18 provided with a wall plate 19 and in each frame is one or more braces 20, according to the length of each outer form. For the formation of the wall 17 the outer 10 forms are stacked one on the other, in staggered relation and may be suitably connected together and braced relative to the collapsible cores during the pouring and tampering of concrete or other plastic material between the inner and outer forms. The frames 18 are adapted to support platform or scaffold brackets 21 so that a wall of considerable height may be conveniently formed. 15
20 In the formation of the concrete block 16 corner pieces 22 are used in connection with the frames 18 and a collapsible core. Any suitable means may be employed for connecting or holding the frames 18 and the corner pieces 22 during the formation of the concrete block 16.

Reference will now be had to Figs. 6 to 30 9 inclusive showing a facing form comprising a frame 23, and in the frame is mounted, preferably by means of dowel pins 24, a facing die 25 preferably made of connected strips of rubber, with metallic reinforcing rods embedded therein. The strips of rubber are preferably triangular in cross section or of such shape as to be readily withdrawn from a plastic facing 26 placed on the wall 17. The plastic facing may be of any material that will harden on the wall 17 in imitation of any building material, for 40 instance bricks or tiles. As shown in Fig. 7 the facing die may be placed against the wall 17 and the interstices filled with the plastic facing 26. When the facing die is withdrawn the plastic facing will leave lines 45 of demarkation similar to laid bricks or tiles, as shown in Fig. 6.

In some instances the facing material may

be placed on the wall 17, as shown in Fig. 9, and then the facing die pressed against the facing material until the rubber strips sink into the facing material and form grooves therein as lines of demarkation in imitation of brick or tile. 50

The various forms herein described constitute an equipment by which a contractor 55 may quickly construct an artistic concrete wall, and it is in this connection that the wall plates 19 of the frames 18 may be in the form of dies for shaping and ornamenting the exterior surface of the concrete wall. 60

While in the drawings there are illustrated the preferred embodiments of my invention, it is to be understood that the structural elements are susceptible to such changes as fall within the scope of the 65 appended claims.

What I claim is:—

1. A collapsible core comprising front and rear wall sections, each comprising a pair of relatively extensible angle plates, toggle 70 means for extending said plates, a lever for the operation of said toggle means, links connecting the front wall sections to the rear wall sections, and means whereby one of said sections may be lifted relatively to the 75 other to facilitate removal of said core from a mold after use.

2. A collapsible core according to claim 1, wherein the angle plates are movable in constant overlapping planes and the front and rear wall sections are adapted to vertical movement and movement one towards the other by virtue of vertically swingable links connecting said front sections to said rear sections. 80

3. A collapsible core according to claim 1, wherein a plurality of said toggle means are provided in the form of links connected at their outer ends to said angle plates and at their inner ends to a common vertically disposed operating bar, and a lever effecting the vertical movement of said bar. 85

In testimony whereof I affix my signature.
COLIN HUTCHINS.
